DESIGN FOR A SHOE SOLE

Oscar Brockman, Louisville, Ky.

Application August 20, 1936, Serial No. 64,496

Term of patent 7 years

To all whom it may concern:

Be it known that I, Oscar Brockman, a citizen of the United States, residing at Louisville, in the county of Jefferson and State of Kentucky, have invented a new, original, and ornamental Design for a Shoe Sole, of which the following is a specification, reference being had to the accompanying drawing, forming part thereof.

In the drawing:

I claim:

The ornamental design for a shoe sole, as shown.

OSCAR BROCKMAN.
